SYSTEM FOR ENERGIZING A CATHODE RAY TUBE

Manfred von Ardenne, Berlin, Germany

Application November 13, 1933, Serial No. 697,739
In Germany November 15, 1932

1 Claim. (Cl. 250—27)

The invention relates to the particular embodiment of mains apparatus for delaying the initiation of the anode potential in Braun tubes. The use of indirectly heated cathodes in tube apparatus, in Braun tubes, acts detrimentally on the life thereof, owing to the long time required for heating the cathode, if the full anode potential becomes effective before the cathode has attained a sufficiently high temperature. Now when using 5 normal mains apparatus the anode potential acquires its full voltage almost instantaneously, whereas the temperature of the cathode, and together therewith the emission, increases only very slowly, and frequently does not attain a sufficiently high value until after an elapse of 10 several minutes. In the interval before the complete emission takes place there is produced a particularly strong cathode fall, which leads to a vigorous bombardment of ions and to a greatly shortened life and a deformation of the cathode, 15 similar to the manner in which, as well known, under-heated cathodes are subject to premature wear or damage in tube apparatus. If the heating period amounts, for example, to 1 minute for 20 an indirectly heated cathode, the dangerous state with the bombardment of ions commences, as experiments have shown after approximately 10 25 seconds. Said cathode fall is particularly dangerous because of the relatively small surface of 30 the highly emissive material.

According to the invention, these disadvantages are to be overcome by the fact that special measures are taken to prevent the full anode potential from becoming effective at a premature 35 stage, and that the anode potential only attains its full effective value when the cathode has reached a sufficiently high temperature and accordingly an adequate emission, which is sufficient to prevent excessive cathode fall in the 40 case of full anode potential, so that a detrimental bombardment of ions is unable to occur.

According to the invention it is possible to accomplish delay in the charging of the condensers of the mains portion, for example by means of 45 series-connected highly ohmic resistances. By the inclusion of highly ohmic resistances in the charging circuit of the rectifier tube the inner resistance of the D. C. generator is diminished, and it is accomplished in reliable fashion that 50 the maximum anode potential is reached automatically only after expiration of the heating period. By the dimensioning of the resistance between the rectifier tube and the condenser, i. e., by dimensioning the time constant of the 55 mains portion, it is possible to perform adapta-

tion to practically any desired cathode. It may also be accomplished that the anode potential in each case does not reach its effective state until the complete emissive temperature of the cathode has been attained both in the case of 5 relatively short as well as long periods of heating of the cathode.

Fig. 1 shows a circuit arrangement of one form of the invention with a short time constant.

Fig. 2 shows a circuit arrangement of another 10 form of the invention with a long time constant.

The invention will now be described more fully with the assistance of certain forms of embodiment. Fig. 1 shows an arrangement as hitherto usual with a mains transformer 1, the secondary winding of which feeds the filament 2 of a Braun tube through the medium of a regulating resistance 3, further the cathode 4 of the rectifier tube 5, and finally the winding 6, which supplies the anode potential. The Wehnelt cylinder 7 of the 20 Braun tube is connected with the anode 8 of the rectifier tube 5. Between the cathode 2 and the Wehnelt cylinder 7 of the Braun tube there is situated a resistance 9, which is bridged by a condenser 10. The anode potential is taken from 25 the condenser 11 and fed to the anode 12 of the Braun tube.

Fig. 2 shows a form of embodiment according to the invention with special dimensioning of the mains portion. The arrangement in itself is 30 the same as in Fig. 1, but according to the invention there is provided in addition to the condenser 11 a resistance 14 and a further condenser 13. If, for example, the condenser 11 is selected $=1\mu\text{F}$, the condenser 13 $=0.25\mu\text{F}$, and the 35 resistance 14 $=5$ megohms, there results in connection with the condenser 11 a charging period of approximately 10 seconds with a time constant of 4.5 seconds, whereas in the case of Fig. 1 the charging period is approximately $\frac{1}{2}$ sec. 40

The possible form of embodiment referred to may undergo numerous modifications within the meaning of the invention. It is essential that in each case measures are taken to ensure that the anode potential does not reach its full value 45 until after the elapse of a certain time which is necessary to raise the indirectly heated cathode to a sufficiently high temperature.

I claim:

In a television arrangement the combination 50 of a Braun tube containing an indirectly heated cathode, a control electrode and an anode, power supply apparatus for energizing the cathode of said tube from a source of alternating current, rectifying means for supplying anode potential 55

to said tube from said source of alternating current, means for delaying the application of normal operating potential to the anode until said indirectly heated cathode has reached a temperature at which detrimental ion bombardment thereupon will not occur, said means comprising

a filter network including parallel connected condensers and a series connected resistance, the condensers and resistance being dimensioned to exhibit a time constant for anode potential supply delay. 5

MANFRED VON ARDENNE.
